(57) **CLAIM**

An ornamental design of a car organizer for wireless accessories, as shown and described.

DESCRIPTION

FIG. 1 is a front, top perspective view of a car organizer for wireless accessories showing my new design;

FIG. 2 is a back side elevational view thereof;

FIG. 3 is an end side elevational view thereof; and,

FIG. 4 is a bottom plan view thereof.

In the figures described below, the patterns and shading techniques on the drawings are intended to represent a fabric material, and is repeated throughout the entire area of the organizer. Additionally, the square pattern on the third flap pocket is understood to represent a mesh material. Finally, the dashed lines on the organizer are understood to represent stitching.
